SPREADER BAR AND TIE ROD ARRANGEMENT
FOR CONCRETE WALL FORMSFrank G. Pauli, Jr., Northville, Mich., assignor to Kwik
Lock Forms Co., Plymouth, Mich., a corporation of
MichiganFiled June 6, 1963, Ser. No. 286,041
8 Claims. (Cl. 25—131)

This invention relates to forms for pouring concrete walls and has to do particularly with a tie rod and spacer bar arrangement for retaining such wall forms in fixed spaced apart relation.

It is an object of this invention to provide a tie rod and spacer bar arrangement of the type described which is simple to assemble and which is adapted to be used with wall forms reinforced with wood walers as distinguished from metal walers.

FIG. 1 is a vertical sectional view through a pair of wall forms held in fixed spaced apart relation by means of the tie rod and spacer bar of this invention.

FIG. 2 is a horizontal sectional view of the arrangement shown in FIG. 1.

FIG. 3 is a sectional view along the line 3—3 in FIG. 2.

FIG. 4 is a side elevational view of the tie rod used in the arrangement.

FIG. 5 is a perspective view of the spreader bar according to the invention.

FIG. 6 is a perspective view of the tie pin employed in the arrangement.

FIG. 7 is an end view of the tie pin shown in FIG. 6.

Referring to FIGS. 1 and 2, there is illustrated a pair of wall forms 10 secured together in spaced relation with the tie rod and spacer bar of the present invention. Each wall form comprises a panel 12 formed of plywood or the like provided with wood reinforcements 14 around its edges and also intermediate the edges of the panel depending on the size of the panel. The reinforcements 14 are preferably and usually pieces of 2 x 4 lumber. The panels 12 are formed at regular intervals with holes 16 therethrough which, when the panels are erected in opposed spaced relation, are adapted to be aligned in a direction transversely of the concrete wall to be formed between the wall forms.

In erecting these wall forms, a spreader bar 18 is engaged with each of the holes 16. As is shown in FIG. 5, each spreader bar 18 comprises a metal strap which is curved in cross section as indicated at 20. At one end, the strap is provided with a pair of depending flanges 22 which are spaced apart in a direction lengthwise of bar 18 a distance slightly greater than the thickness of the wall panels 12. Flanges 22 can be welded or otherwise attached to one end of spacer bar 18. Flanges 22 have rounded lower edges 24 and the overall height of these flanges is such as to permit the end of the spreader bar to be inserted through the openings 16 and then pushed downwardly to engage the flanges with the lower edges of the holes 16. Adjacent the outer end of spreader bar 18, a rectangular opening 26 is formed therein at a predetermined distance from the flanges 22 for a reason which will presently become apparent. The curvature in transverse section of the spreader bar 18 corresponds generally with the diameter of the holes 16 so that the spreader bars will seat rather snugly in the holes 16. However, the arcuate extent of the spreader bar 18 is relatively short as compared to the circumference of the hole 16. Note FIG. 3, for example.

As is customary, a tie rod 28 is extended through the aligned openings 16 in the opposed wall forms. Tie rods 28 have a length substantially greater than the distance

between the outermost edges of the two wall forms 10. Tie rods 28 taper in length from one end to the other. For example, one standard tie rod has a diameter of $1\frac{1}{16}$ " at the large end and $\frac{5}{8}$ " at the small end. With tie rods of these dimensions, the holes 16 in panels 12 are preferably about 1" in diameter. Tie rods 28 are provided with an axially elongated hole 30 at the smaller end and a plurality of axially elongated holes 32 adjacent the larger end of the tie rod.

After the tie rods are extended through the aligned holes in the wall forms and seated in spreader bars 18 with their opposite ends projecting outwardly beyond the outer faces of the wall forms as illustrated in FIG. 1, wood reinforcing walers 34 are arranged thereon. The walers 34 preferably comprise two 2 x 4's 36 which are secured together in spaced relation by spacer blocks 38. Walers 34 are engaged over the ends of the tie rods 28 as illustrated. The wall to be poured will have a thickness corresponding to one of several standard thicknesses.

In any event, when the wall panels 12 are spaced apart a distance corresponding to the standard thickness of the wall to be poured and the hole 30 at the smaller end of tie rod 28 is aligned vertically with the hole 26 in one of the spreader bars 18, the hole 26 in the other spreader bar 18 will be aligned vertically with one of the holes 32 adjacent the larger end of tie rod 28. Speaking more accurately, the axially outer ends of the holes 26 in spreader bars 18 will be located inwardly in a direction toward the wall panels 12 with respect to the axially outer ends of the aligned holes 32 in the tie rod 28.

The whole assembly of wall forms 10, walers 34, tie rod 28 and spreader bars 18 is then locked in rigid assembled relation by means of tie pins 40. Each tie pin, as is best illustrated in FIG. 7, comprises a short length of structural steel channel having a web portion 42 and a pair of legs or flanges 44. A wedge 46 is welded to the inner side of web 42 centrally between legs 44. A substantial portion of web 42 is notched or cut out as at 48 so that the angled edge 50 of wedge 46 overlies the opening 48 in the tie pin. The tip 52 of wedge 46 is preferably coplanar with the outer face of web 42 as is shown in FIG. 1. It will be noted that the opening 48 has a width less than the distance between the inner faces of legs 44 so as to present ledges 54 along the inner side of these legs adjacent the opening 48. As a practical matter, the width of opening 48 is only slightly wider than the width of spreader bars 18 so that the tie pin can straddle the spacer bars. To secure the assembly together so that the wall forms will be held rigidly in spaced apart relation, the tie pins 40 are driven downwardly against the outer edges of walers 34 so that the wedge member 46 is extended through the aligned openings in the spacer bars 18 and the opposite ends of the tie rods 28. It will be appreciated that as the tie pins 40 are driven downwardly, the angled edge 50 of the wedge member 46 engages the outer ends of the elongated openings in the spreader bars 18 and tie rods 28 so as to rigidly interconnect the two spacer bars 18 with each tie rod 28 and by reason of the flanges 22 on the spreader bars 18, to rigidly interconnect each wall form 10 with the tie bars. Furthermore, it will be appreciated that by forming the tie pins 40 as channel-shaped members, these tie pins are relatively strong and furthermore engage the outer edges of the 2 x 4 walers 34 with broad flat faces. Thus, there is not too great a tendency for the tie pins 40 to dig into and gouge the end faces of the 2 x 4's 36 of walers 34.

I claim:

1. In a concrete wall form construction comprising a pair of spaced apart opposed wall forms which define the opposite faces of the concrete wall poured therebetween, the wall forms comprising panels having rein-

forcements secured to the outer faces thereof and having transversely aligned openings therein, means for retaining the wall forms in fixed spaced apart relation comprising a tie rod extending through aligned openings in the opposed panels, said tie rod extending transversely through the panels and outwardly beyond the reinforcements on the wall forms, said tie rod having openings therethrough in the end portions thereof beyond the reinforcements, a pair of spreader bars, each spreader bar having one end thereof hooked to the panel at said opening and locked thereto against movement transversely of the panel, said spreader bars extending outwardly of the panels beyond said reinforcements, one adjacent each of the opposite ends of the tie rod, each spreader bar having an opening therein registering with an opening in the end portion of the tie rod, said registering openings lying outwardly beyond the plane of said reinforcements and wedge means driven through said registering openings at each end of the tie rod and engaging said reinforcements.

2. The combination called for in claim 1 wherein each spreader bar is fashioned with a U-shaped hook portion at one end thereof engaging the panel, the legs of said U-shaped hook portion being spaced apart approximately the thickness of the panel so as to straddle and embrace the opposite faces of the panel at said opening.

3. The combination set forth in claim 1 wherein each spacer bar is arcuately dished in transverse section and the tie rod is seated in the arcuately dished portion thereof.

4. The combination called for in claim 3 wherein the radius of the dished portion of the tie rod corresponds generally with the radius of the hole formed in the panel.

5. A spreader bar for use with wall forms comprising a metal strap which is of arcuate configuration in cross section, said strap having an axially elongated opening therein adjacent one end of the strap, the opposite end of the strap having a pair of axially spaced flanges depending therefrom.

6. A spreader bar as called for in claim 5 wherein the free ends of said flanges are arcuately shaped.

7. The combination called for in claim 1, wherein the spreader bar comprises a strap having a pair of transversely extending legs at one end thereof spaced longitudinally of the strap and projecting to one side of the strap to form with the end portion of the strap a U-shaped hook which is adapted to be inserted through the opening in the panel, so that the legs of the strap embrace and straddle the opposite faces of the panel.

8. The combination called for in claim 7, wherein the length of the end-most leg on the strap is approximately equal to the diameter of the hole in the panel.
